CREEPING TRACTION MECHANISM

Original Filed Feb. 7, 1921 3 Sheets-Sheet 1

Fig. 1.

A technical drawing of a cylindrical component. At the top, there is a small circular feature labeled '12'. Below it, a rectangular slot or opening is labeled '10'. To the right of the cylinder, a small circular feature is labeled '13'. A horizontal line extends from the right side of the cylinder, with a small circle labeled '3' at its end. The number '7' is also present on the right side of the cylinder.

UNITED STATES PATENT OFFICE.

SVANTE R. W. M. BAGER AND WERNER LEHMAN, OF SOUTH MILWAUKEE, WISCONSIN,
ASSIGNORS TO BUCYRUS COMPANY, OF SOUTH MILWAUKEE, WISCONSIN, A COR-
PORATION OF WISCONSIN.

CREEPING TRACTION MECHANISM.

Application filed February 7, 1921, Serial No. 443,164. Renewed January 21, 1928.

To all whom it may concern:

Be it known that we, SVANTE R. W. M. BAGER and WERNER LEHMAN, both citizens of the United States, and residents of South Milwaukee, in the county of Milwaukee and State of Wisconsin, have invented certain new and useful Improvements in Creeping Traction Mechanism; and we do hereby declare that the following is a full, clear, and exact description thereof.

This invention relates to creeping traction mechanism for use, primarily, in connection with heavy, portable machinery, such as power excavators and the like.

The general aim of the invention is to simplify, lighten and otherwise generally improve the construction of devices of this character.

The operating machinery in power excavators and similar apparatus is ordinarily carried by a sub-base or frame usually mounted upon wheels or otherwise equipped to provide portability. This frame is commonly of a heavy construction, in order to provide the necessary strength and rigidity for supporting the operating parts and for withstanding the severe working stresses characteristic of apparatus of this type. A frame having the requisite strength and rigidity for this purpose, but of an improved and comparatively light construction, is disclosed in the copending application of S. R. W. M. Bager, Serial No. 443,106, filed February 7, 1921.

One specific object of the present invention is the provision of a creeping traction mechanism, especially fitted for use with a frame, such as that described in the application referred to.

Another object is the provision of a creeping traction mechanism for excavators and the like; so constructed and arranged as to avoid the requirement for auxiliary frames, so commonly employed in devices of this character.

Other objects and advantages will later appear.

One embodiment of this invention is illustrated in the accompanying drawings, in which:

Figure 1 represents a plan view of a main supporting frame of an excavating machine having the principles of this invention embodied therein;

Figure 2 is a side elevational view of the parts shown in Figure 1 and particularly illustrating the creeping traction mechanism;

Figure 3 is a transverse sectional view taken substantially on the plane of the line 3-3 of Figure 1;

Figure 4 is a similar view on the plane of the line 4-4 of Figure 1;

Figure 5 is a plan view of a pair of tread belt links looking at the inner side thereof;

Figure 6 is a transverse sectional view through one of these links on a plane indicated by the line 6-6 of Figure 5;

Figure 7 is an enlarged elevational view of a portion of one of the driving tumblers and a plurality of the tread belt links;

Figure 8 is a fragmentary plan view of the rim of one of the driving tumblers, and

Figure 9 is a detailed elevational view of one of the tape-up structures for the front axle.

The creeping traction mechanism selected for illustration is shown applied to the main supporting frame of a power excavator. This frame is substantially the same as that described in the copending application above referred to. It is substantially rectangular in shape and comprises a pair of longitudinally spaced side bars or sills 1 and end bars or sills 2. The middle portion of this frame is braced by two pairs of intermediate transverse sills or bars 3 and 4, all of which bars as well as the side and end bars are preferably of heavy I-beam construction. A pair of side cover plates 5 are disposed on and extend inwardly from the top flanges of the side bars 1, and these plates are riveted to said side bars and the transverse bars, while a transverse cover plate 6 is disposed on each pair of the intermediate transverse bars 3 and 4 and riveted to their flanges.

A rack and track member preferably in the form of a single annular casting 7 is mounted on the several cover plates, it resting particularly on the cover plates 6 supported by the transverse bars 3 and 4, and overlapping the side cover plates 5 and the intermediate portions of the side bars 1 (see Figure 1). The casting 7 is riveted as at 8 to the several cover plates and is thus retained in proper relation to the different elements of the main frame. The rack and track member includes inwardly extending

radial arms 9 which merge into a central bearing sleeve 10, and the portions of these arms adjacent their connection with the annular portion of the casting 7 are transversely widened to provide attaching plates 11 which overlie the transverse bars 3. The central bearing sleeve 10 receives a vertical propulsion shaft 12 which is connected with the machinery drive mechanism (not shown), and the upper end of said sleeve also forms a trunnion for the revolving frame (also not shown) which rests on the track portion of the casting 7.

The rack and track casting is further secured to the other parts of the frame by pairs of tie bolts 13 which are passed through said attaching plates 11, each pair of said bolts straddling a respective transverse bar 3 and being connected at their lower ends by a suitable tie plate member to be later described. These bolts 13 obviously take up the tilting stresses involved in the operation of the heavy machinery mounted on the main supporting frame and relieve such stresses from the various rivets, including the rivets 8.

In adapting this main supporting frame for a creeping traction mechanism, two slide bars 14 are secured under the forward portion of each side bar 1 longitudinally thereof, and a front axle 15 is disposed transversely across the frame, the same being supported at its opposite ends by means of a pair of split clamp collars 16. Each of these split clamp collars 16 has an upper flat bearing face for engagement with a similar face of its respective slide bar, and also is provided with an upwardly disposed hook extension 17 slidably embracing an edge of the co-operating slide bar 14. The axle 15 carries idle tread belt wheels 18, and the slidable connections of the collars 16 with the slide bars 14 provide for take-up adjustment of such wheels, this adjustment being effected by screws 19 having their forward ends squared and engaged in squared sockets in the collars 16. The rear ends of the screws are passed through bracket ears 20 depending from the rear ends of the slide bars 14 and have holding nuts 21 threaded thereon at the forward sides of the bracket ears for engagement with the latter.

The rear end portions of the side bars 1 carry a pair of depending axle bearings 22 through which extends the rear axle 23 of the vehicle, one end portion of the axle being directly journaled in its bearing 22, while the other end portion of the axle extends through and is journaled in a sleeve 24 which in turn is directly journaled in the other bearing 22. A drive tumbler 25 is keyed on the outer end of the sleeve 24, while a drive tumbler 26 is keyed on the remote outer end portion of the axle, creeping tread belts formed of series of links

27 being trained about these tumblers and about the idler wheels 18 carried by the ends of the front axle 15, the structure of these belts and tumblers being hereinafter described in detail.

The inner end of the sleeve 24 terminates adjacent the center of the axle 23 and carries a fixed bevel gear 28 which meshes with a similar gear 29 carried by a countershaft 30 extending longitudinally of the vehicle 75 frame and having bevel gear connection 31 with the vertical drive shaft 12. Said bevel gear 29 also meshes with a like gear 32 loosely mounted on the axle, said gears 28 and 32 being thus spaced apart and receiving a 80 double clutch member 33 splined on the axle therebetween for selective engagement with the inner clutch face of either thereof. In assembling this clutch and gear structure, a key 34 is set in the axle to provide the 85 spline connection for the clutch member 33, and collars 35 are disposed on the axle at the end of this key to limit inward movement of the bevel gears 28 and 32.

The gear 29 is continuously driven for 90 whichever propulsive action is desired, and thus when the clutch member 33 is engaged with the gear 28, the sleeve 24 is locked to the axle shaft and both of the drive tumblers 25 and 26 will be rotated in the same direction to procure direct propulsion of the vehicle in either direction in accordance with the direction of rotation of the gear 29 which in practice would be provided with reversible drive means. When the clutch is in 100 neutral however, the drive tumbler 25 alone will be rotated, which will procure a turning movement of the vehicle in either direction, in accordance with the direction of rotation of the gear 29. When, however, it is 105 desired to turn the vehicle about on its own axis, the clutch 33 is engaged with the gear 32, thus locking said gear 32 to the axle and effecting rotation of the sleeve and axle, and their carried drive tumblers, in opposite 110 directions, whereupon the vehicle will not be propelled, but merely turned on its axis to properly position its carried mechanism with respect to the work. We have thus provided an exceedingly simple and readily 115 controlled means for selectively operating the drive tumblers.

Each of the creeping tread belt links 27 comprises a casting having a smooth tread surface portion curved on an arc having a center approximately corresponding to the center of the tumbler about which the tread belt turns, and ribs 36 projecting inwardly from said tread surface portion and merged into a skeleton inner wall which carries a 120 pair of channel flanges 37 spaced apart a distance corresponding to the width of the tumbler rims. Each link carries at one side a pair of pivot ears 38 and has its other side 125 portion cut away to receive the pivot ears 130

of the next adjacent link, pivot pins 39 being passed through the interengaging parts of the links and held in place by relatively smaller retaining pins 40, the same being 5 extended transversely through outer ends of the pivot pins and engaged in the adjacent corners of the corresponding links.

Each of the tread belt wheels and tumblers comprises a hub portion *a* mounted on the 10 respective axle end and carrying a radial web *b* widened at its outer periphery to provide the wheel rim *c* fitting between the channel flanges 37 of the links, said web being formed with a series of radial brace 15 ribs *d* taperingly increased in depth toward the hub portion. On the idler wheels of the front axle these ribs terminate short of the guide channel of the tread belt, but on the tumblers 25 and 26 the outer ends of the 20 ribs are enlarged in slightly oval elevation to form driving sprockets *e* that are adapted to engage between the opposed ends of the channel flanges 37 which thus define driving recesses.

25 It is to be noted that while the tread belts and the individual links thereof are relatively wide, the wheels 18 and tumblers 25 and 26 are relatively narrow, and although the latter engage the former only in the center, the belts are retained in proper operative position at all times. This is largely occasioned by the individual guide channel on each belt link together with the means 30 for transmitting power from the driving tumblers to the latter. In other words the flanges 37 in addition to forming guide channels define sprocket receiving recesses between their opposite ends, and these recesses decrease in size as the tread belts pass around 35 the tumblers so that the sprockets thereof are relatively snugly engaged. This constant changing of the size of the sprocket receiving recesses discourages the tendency of any materials clogging or caking therein 40 and the consequent exclusion of the sprockets.

45 It will be noted from the foregoing description that each traction unit is connected to the main frame through the axles 15 and 50 23 which are secured to and project outwardly beyond the sides of the frame. These axles thus constitute cantilever supports by which the traction units are mounted on the frame.

55 Cantilever supports are provided for the intermediate stretches of the tread belts, these each including a bracket 41, the inner end portion of which forms a tie plate member 42 for a respective pair of tie bolts 13, the outer end portion on the other hand being a stub axle 43. As most clearly shown in Figure 4, each of the brackets 41 underlies the main supporting frame and bears against the side bar 1 thereof, the stub axle 43 extending into the plane of the center of a

tread belt. Intermediate idler wheels or rollers 44, which are substantially similar to the wheels 18, are journaled on the stub axles 43, their peripheries being adapted to run in the guide channels of the tread 70 belts and to engage both the upper and lower stretches thereof. For instance the axis of the stub axles 43 is below the horizontal plane of the axis of the front and rear axles and the wheels 44 retain the 75 lower stretches of the tread belts substantially horizontal and hold the same in working contact with the ground, the upper stretches, on the other hand, while supported by said wheels 44 are permitted to 80 sag.

85 As a result of the foregoing described construction it is possible to effectively mount a creeping drive mechanism at one side of a supporting frame on which different types of operating machinery can be carried, and entirely and adequately support the same without the addition of the usual auxiliary frames. We are thus enabled to build a relatively light creeping unit and 90 also a main supporting frame of relatively great strength and lightness.

95 It will be obvious from the foregoing description taken in connection with the accompanying drawings that various modifications and changes may be made from the herein described preferred embodiment of the invention, without departing from the principles thereof or sacrificing any of 100 the advantages.

We claim:

1. In a creeping traction mechanism, a supporting frame including a pair of side bars, a plurality of transverse connecting bars, a superstructure track mounted on said bars, and tie bolts extended through said track and engaged with certain of said transverse bars, brackets extending outwardly of the side bars of the frame and having their inner ends secured by said tie bolts, said 110 ends forming tie plates for the latter, supporting axles carried by the frame and having their ends extended beyond the side bars, endless tread belt receiving wheels on the ends of the axles, an endless tread disposed around each co-operating pair of 115 wheels, and rollers on said brackets for engaging intermediate stretches of the belts.

2. In a creeping traction mechanism, a supporting frame including a pair of side bars, a pair of end bars connecting the side bars, a pair of spaced intermediately disposed transverse bars connecting said side bars, a superstructure track mounted on the side and intermediate bars, a plurality of pairs of tie bolts extending through the track, the bolts of each pair straddling one or the other of said intermediate transverse bars, brackets extending outwardly of the side bars of the frame, each of said brackets 130

- having its inner end secured by one of said pairs of tie bolts, said ends forming tie plates for said pairs of bolts, supporting axles carried by the frame and having 5 their ends extended beyond the side bars, endless tread belt receiving wheels on the ends of the axles, an endless tread belt disposed around each co-operating pair of wheels, and rollers on said brackets for 10 engaging the intermediate stretches of the belts.
3. In a creeping traction mechanism, a supporting frame including a pair of side bars, a plurality of transverse connecting 15 bars, a superstructure track mounted on said bars, and tie bolts extended through said track and engaged with certain of said transverse bars, said tie bolts being spaced inwardly of the side bars, brackets extending 20 outwardly of the side bars of the frame and having their intermediate portions in bearing engagement with the under surface thereof, said brackets having their inner ends secured by said tie bolts, said ends forming 25 tie plates for the latter, supporting axles carried by the frame and having their ends extended beyond the side bars, endless tread belt receiving wheels on the ends of the axles, an endless tread belt disposed around 30 each co-operating pair of wheels, and rollers on said brackets, said rollers being located outwardly of the side bars of the frame and engaged with intermediate stretches of the belts.
- 35 4. In a creeping traction mechanism, a rigid supporting frame including a pair of side sills, brackets beneath said sills, said brackets having brace members extending inwardly of the sills and secured to said 40 frame adjacent their inner ends, said brackets having axle members extending outwardly of said sills, wheels on said axle members, and an endless tread belt at each side of said frame providing endless tracks for said 45 wheels.
5. In a creeping traction mechanism, a rigid supporting frame including a pair of side sills, brackets beneath said sills, said brackets having brace members extending 50 inwardly of said sills and secured to said frame adjacent their inner ends, said bracket having axle members extending outwardly of said sills, axles extending transversely of said frame and projecting outwardly be-
- yond said sills, wheels on said axle members and on the projecting ends of said axles, and endless tread belts at opposite sides of said frame trained about said wheels.
6. In a creeping traction mechanism the 60 combination of a rigid base frame, axles mounted beneath said frame and projecting beyond the sides thereof, a series of wheels at each side of said frame mounted on the projecting ends of said axles, respectively, 65 the wheels of each series having relatively narrow rims disposed in a common plane, a relatively broad endless tread belt comprising a series of relatively wide slab-shaped links closely connected to form a substantially continuous tread surface, hinge connections between said links disposed within the plane thereof to maintain the continuity of said surface, and a centrally disposed relatively narrow guide channel formed 70 along the inner surface of each tread belt in which all the wheels of a series engage.
7. In a creeping traction mechanism the combination of a rigid base frame, axles mounted beneath said frame and projecting 80 beyond the sides thereof, a series of wheels including end wheels and intermediate wheels at each side of said frame mounted on the projecting ends of said axles, respectively, the wheels of each series having relatively narrow rims, a relatively broad endless tread belt trained about each series of 85 wheels, each tread belt comprising a series of slab-shaped links closely connected to form a substantially continuous tread surface, 90 hinge connections between said links disposed within the plane thereof to maintain the continuity of said surface, and upstanding flanges on the inner surfaces of said links forming a central runway for 95 all the wheels of a series, said runway being disposed well within the edges of the tread belt.

In testimony that we claim the foregoing, we have hereunto set our hands, WERNER 100 LEHMAN having subscribed at South Milwaukee, in the county of Milwaukee and State of Wisconsin, and SVANTE R. W. M. BAGER having subscribed at Memphis, in the county of Shelby and State of Tennessee. 105

WERNER LEHMAN.
SVANTE R. W. M. BAGER.
